UNITED STATES PATENT OFFICE.

JOHN H. YOUNG, OF BARTLESVILLE, OKLAHOMA.

GUN-SUPPORT.

1,309,560.

Specification of Letters Patent.

Patented July 8, 1919.

Application filed September 21, 1918. Serial No. 255,131.

To all whom it may concern:

Be it known that I, JOHN H. YOUNG, a citizen of the United States, residing at Bartlesville, in the county of Washington and State of Oklahoma, have invented a new and useful Gun-Support, of which the following is a specification.

This invention relates to a support for machine guns and the like, one of its objects being to provide a disappearing support of inexpensive construction which can be transported readily in a knockdown condition and quickly set up for use and operated so as to hold a gun at a desired elevation above the ground and, if necessary or desirable, lower the gun to the ground where it will be concealed within a trench or wherever located.

With the foregoing and other objects in view which will appear as the description proceeds, the invention consists of certain novel details of construction and combinations of parts which will be hereinafter more fully described and pointed out in the claim, it being understood that various changes may be made in the construction and arrangement of the parts without departing from the spirit or sacrificing any of the advantages of the invention as set forth in the appended claim.

In the accompanying drawings the preferred form of the invention has been shown.

In said drawings—

Figure 1 is a side elevation of the support the lowered position thereof being indicated by dotted lines.

Fig. 2 is a plan view.

Fig. 3 is a section on line 3—3, Fig. 1.

Fig. 4 is an enlarged section through one of the joints of the device.

Referring to the figures by characters of reference, 1 designates the sides and 2 the ends of the base frame of the support, said sides and ends being connected by T-fittings, elbows or the like indicated at 3 and being formed preferably of pipe of standard size. Mounted for rotation on each of the ends 2 close to each of the connections 3 is a T-fitting 4. Standards 5 of lengths of pipe are in engagement with these fittings 4 and are provided, at their upper ends, with T-fit-

tings 6 in which are secured the ends of upper end members 7 formed of pipe. A pair of T-fittings 8 are mounted for rotation on each of the members 7 close to the fittings 6 and the fittings 8 on the opposed members 7 are connected by upper side members 9, thus to form an upper or top frame. A plate 10 is mounted on and secured to the members 9 and the gun or other object to be supported is adapted to be mounted on this plate.

In using the device the parts are assembled as described and the support is set up at the point of use with the base frame resting on the ground. Posts 11 are erected between the end members 2 with their upper ends supporting sheaves 12. Each post extends above the ground a distance somewhat less than the length of the standards 5 and the sheaves 12 support cables 13 which are fastened at one end to the front end of the top frame and at their other ends to a winding drum or windlass 14 mounted on a standard 15 and having a hand wheel 16 for operating it. Stop stakes 17 are positioned in the paths of the standards 5 for supporting the standards when the top frame is lowered. These stakes may be provided in their upper ends with recesses constituting seats for the standards 5, as shown at 18.

By winding the cables 13 on the windlass after a gun has been mounted on the plate 10, said plate, with the gun thereon will be swung or elevated a desired distance and held by fastening the windlass against movement in the opposite direction. By unwinding the cables, the top frame of the support will be lowered until the standards come against their seats 18.

What is claimed is:—

A knock down gun support formed of detachably connected pipes and joints and including a base frame and a top frame, standards connecting and pivotally mounted on the ends of the frames, a plate secured to the top frame standards erected between the ends of the base frame and extending upwardly through the top frame when the support is lowered, elevating cables extending over and connected to the top frame and guided over the standards and downwardly to the front end of the upper frame when said frame is in

lowered position, means for taking up or paying out the cables to raise or to lower the top frame and its standards, and stop devices in the paths of the standards for supporting the standards and top frame in lowered positions.

In testimony that I claim the foregoing

as my own, I have hereto affixed my signature in the presence of two witnesses.

JOHN H. YOUNG.
